(57) **CLAIM**

The ornamental design for an optical reading device, as shown and described.

DESCRIPTION

FIG. 1 is a side front perspective view of an optical reading device.

FIG. 2 is a top rear perspective view of the optical reading device shown in FIG. 1.

FIG. 3 is a top front perspective view of the optical reading device shown in FIG. 1.

FIG. 4 is a front view of the optical reading device shown in FIG. 1.

FIG. 5 is a top view of the optical reading device shown in FIG. 1.

FIG. 6 is a side view of the optical reading device shown in FIG. 1.

FIG. 7 is a rear view of the optical reading device shown in FIG. 1; and,

FIG. 8 is a bottom view of the optical reading device shown in FIG. 1.

1 Claim, 4 Drawing Sheets
